METHOD OF MAKING PHOTOGRAPHIC PRINTS

Erich Loening, Berlin-Neutempelhof,
GermanyApplication March 24, 1932, Serial No. 600,993,
and in Germany April 1, 1931

9 Claims. (Cl. 95—5.6)

My invention relates to a method of making photographic prints from printing forms showing illustrations, type matter, or both.

It is an object of my invention to provide a method by which better photographic prints are obtained than heretofore.

To this end, I apply to the background and to the surface of a printing form coloring matter of distinct actinic properties.

10 For instance, I may apply a non-actinic or less actinic color to the background, and an actinic or more actinic color to the surface of the form, or vice versa.

It has already been proposed to coat the form 15 throughout with an inactinic layer and to wipe the layer away from its surface, but it has been found that the contrast between the type or the like at the surface, and the background, is not strong enough, particularly if the form has already 20 been printed from and has lost some of its brightness at the surface.

As it is difficult to apply the layer of coloring matter to the form without partly filling in the 25 interstices between its types or lines, if mechanical means such as a brush or the like, are used, I prefer to spray the color to the form.

In most of the existing printing methods, and 30 particularly for offset and photogravure printing, a reproduction is first made by book printing, usually on transparent or translucent material, such as the material known as "cellophane", thin paper or the like, and the type etc. on this reproduction is made opaque by powdering it with black lead, 35 bronze powder, or the like. This reproduction is then copied on stone, zinc, pigment paper, or the like.

The more transparent the bearer, and the more 40 defined and uniformly opaque the reproduction on the bearer, the better will be the prints from the bearer.

However, it is rather difficult to obtain a clear 45 and uniformly opaque reproduction on such thin material. Particularly if the bearer is perfectly transparent, such as cellophane or the like, and the print does not readily adhere to it, as is the case if illustrations and type are etched together as in stereotype printing, great care and skill are required. All the same, it is always necessary to treat the reproduction with opaque powder which 50 results in a perceptible blurring of contours.

It has been suggested in view of these difficulties not to print on transparent or translucent material at all, but to make a print on art paper, which is less difficult, to make a photographic negative from the print and a diapositive from the

negative. This method results in a satisfactory reproduction, with opaque and clearly defined lines, but is obviously rather complicated.

According to my method, all complications are eliminated and in particular it is not necessary to 60 powder the reproduction while at the same time clear definition and uniform opacity are obtained to an extent which was hardly practicable with the existing and much more complicated methods.

65 In the accompanying drawing, the manner in which my method may be performed, is illustrated by way of example.

In the drawing

Figs. 1 and 2 show two methods of coloring the 70 background and the surface of a form in plan.

Fig. 3 is a cross section of a form.

As explained, the surface and the background must be colored in such manner that the actinic 75 properties of the surface are as different as possible from those of the background.

This may be effected in two ways:

(a) The form is coated throughout with a very 80 inactinic color, preferably black or red, and white color is applied to the surface by a roller;

(b) The form is coated throughout with white, with reflecting aluminium bronze, or with some other very actinic color, and black color is applied to the surface.

Case (a) is illustrated in Fig. 1, and case (b) 85 in Fig. 2. It will appear that the type 2 in Fig. 1 and 4 in Fig. 2, is very markedly contrasted with the background of the form 1 in Fig. 1 and 3 in Fig. 2.

As mentioned, it is difficult to apply the color 90 to the form with a brush or other mechanical means without blurring thin lines by the color entering the interstices 5 and 6 between the types, as shown in Fig. 3. This is entirely eliminated by spraying the color.

Coating the form with an inactinic layer of 95 varnish or the like, and exposing the type, as mentioned above, is not enough. The contrast obtained in this manner between the surface and the background is not so marked as to yield a 100 clearly defined and uniformly opaque reproduction. Conditions are still less favorable if the type has been used and its surface has become dull, or if lines of brass or etchings in zinc or copper are in the form.

The influence of properties of the material is 105 eliminated in my method of double coloring the form, and a uniform and very marked contrast of surface and background is obtained.

Assuming that the form has been coated 110

throughout with an inactinic color, say black, highly actinic properties are imparted to its surface by applying thereto a color such as white or silver, etc. In order not to be compelled to employ a color of very high covering properties, the black or other inactinic color may be removed from the surface by a wiper or the like, but this is not indispensable. If the form is coated with an actinic color, such as white, the surface is coated 10 with an inactinic color, such as black.

From the form which has been colored as described, a negative is made on very "hard" plates or the like by a camera, or preferably by one of the known reflex methods. Obviously the negative 15 may be made not only on transparent bearers, such as plates or films, but on bearers of any other material, for instance, paper.

It will be understood that the object of my method is to increase the contrasts of the original, 20 i. e. the form, so that a well-contrasted negative will be obtained. It has been found that with the usual reducing and intensifying methods the light portions of the negative become as transparent as glass but the dark portions are not always 25 opaque enough. Thus, while the background is like glass, the type is too light, or conversely, the type is perfectly transparent but the background is not dark enough.

In order to obtain full-tone negatives, in which 30 the type or the background, as the case may be, is as opaque as required, the transparent portions of the negative are removed altogether and a washed-out relief is obtained. This may be effected by materials and methods which are old 35 in photography.

Such methods are, for instance, as follows:

1. Developing with tanning developers and removing the unexposed portions;
2. Developing with non-tanning developers and 40 removing of the exposed portions with hydrogen peroxide or other agents.

With these methods, particularly for films or 45 glass plates, the unremoved portions of the sensitized layer can be made as opaque as required by repeated developing, intensifying, coloring or the like, so that a very contrasted negative is obtained, with the exposed portions quite opaque and the unexposed ones transparent as glass.

In reducing my invention to practice, I may 50 proceed as follows:

1. The form is sprayed with good black zapon lacquer and coated with covering white color on its surface. A film is exposed through the bearer of the sensitized layer and developed with pyrocatechol without sulfite. The non-hardened portions of the sensitized layer are removed with warm water and the type which, as known, contain the major portion of the silver in unreduced condition, are reduced by any suitable developer or sodium sulfate and intensified, if required. The result is a positive copy with glassy background and clearly defined opaque type.

2. The form prepared as under (2) is photographed on sensitized paper in a camera and the negative developed with non-tanning developer. The developed portions with the gelatine are removed by treatment with acidulated solution of hydrogen peroxide, until the paper base is exposed. The non-removed portions of the sensitized layer are blackened completely by a second developing. A negative of the type on paper is obtained, with white (paper) type on a dark black background.

I claim:

1. The method of making photographic full-tone prints from printing forms, comprising spraying on to the background, and applying to the surface, of a printing form coloring matter of contrasted actinic properties, and photographing the form. 80

2. The method of making photographic full-tone prints from letterpress printing forms, comprising spraying the form with inactinic coloring matter throughout, applying to the surface of the form actinic coloring matter, and photographing the form. 85

3. The method of making photographic full-tone prints from letterpress printing forms, comprising spraying the form with actinic coloring matter throughout, applying to the surface of the form inactinic coloring matter, and photographing the form. 90

4. The method of making photographic full-tone prints from letterpress printing forms, comprising applying to the background and to the surface of a printing form coloring matter of contrasted actinic properties, photographing the form, and removing the light portions of the 100 photograph.

5. The method of making photographic full-tone prints from letterpress printing forms, comprising applying to the background and to the surface of a printing form coloring matter of contrasted actinic properties, photographing the form and forming a relief by removing the parts not exposed to light by dissolving with a non-tanning developer. 105

6. The method of making photographic full-tone prints from letterpress printing forms, comprising applying to the background and to the surface of a printing form coloring matter of contrasted actinic properties, photographing the form and forming a relief by developing the negative with non-tanning developers and by dissolving the exposed portions with hydrogen peroxide. 110

7. The method of making photographic full-tone prints from letterpress printing forms, comprising applying to the background and to the 120 surface of a printing form coloring matter of contrasted actinic properties, photographing the form and forming a relief by treating the exposed film with developers and dissolving agents, and making the sensitized layer as opaque as required by repeated developing of the nonremoved portions. 125

8. The method of making photographic full-tone prints from letterpress printing forms, comprising applying to the background and to the 130 surface of a printing form coloring matter of contrasted actinic properties, photographing the form and forming a relief by treating the exposed film with developers and dissolving agents, and making the sensitized layer as opaque as required by coloring the nonremoved portions. 135

9. The method of making photographic full-tone prints from letterpress printing forms, comprising applying to the background and to the 140 surface of a printing form coloring matter of contrasted actinic properties, photographing the form and forming a relief by treating the exposed film with developers and dissolving agents, and making the sensitized layer as opaque as required by intensifying the nonremoved portions. 145

ERICH LOENING.
